UNITED STATES PATENT OFFICE

2,049,592

PRINTING MACHINE

Frank P. Sager, Los Angeles, Calif., assignor to
 National Postal Meter Company, Los Angeles,
 Calif., a corporation of California

Application May 24, 1935, Serial No. 23,160

1 Claim. (Cl. 101—91)

This invention relates to a printing machine adapted to the printing of postage stamps upon mail matter, and is of the multi-denomination type, and more particularly to means for locating and maintaining the selected multi-denomination printing die in correct printing register and the multi-ratio driving means in correct driving relation during the printing action of the machine.

Unless the selected multi-denomination printing die correctly registers with the printer head of the machine, the printing of the value in the stamp may not be clear and distinct; as, for example, should the selected value printing die be turned but slightly from its correct printing position, the top or bottom of the figure will only be printed. In some cases it has been found that the value printing die has been so far out of register during the printing action of the machine as to render the partially printed figure practically illegible.

It is therefore one of the principal objects of this invention to provide means operable for locating and maintaining the selected multi-denomination printing die in correct printing register during the printing action of the machine, whereby the selected value will be clearly and distinctly printed in the stamp.

A further object is to provide means for maintaining the selected multi-ratio driving means located in correct driving relation during the printing action of the machine.

Other objects and advantages of the invention will become apparent as the nature of the same is more fully understood from the following description and accompanying drawings, wherein is set forth what is now considered to be a preferred embodiment. It should be understood, however, that this particular embodiment of the invention is chosen principally for the purpose of exemplification, and that variations therefrom in details of construction or arrangement of parts may accordingly be effected and yet remain within the spirit and scope of the invention as the same is set forth in the appended claim.

In the drawings:

Figure 1 illustrates a side elevational view of the printing machine partially in section.

Figure 2 illustrates a sectional view taken substantially in the plane of line 2—2 of Fig. 1.

Figure 3 illustrates an enlarged fragmental view of the printer head, multi-denomination printing means, selector, and locating means. This figure shows these parts in the positions they will assume while the machine is at rest.

Figure 4 illustrates a view similar to Figure 3, but showing the position the parts will assume during the printing action of the machine.

Figure 5 illustrates on an enlarged scale, a partial sectional view of the printer head, multi-ratio driving means, the locating means, and the meter. The figure shows the parts in the position which they will normally assume while the machine is inactive.

Figure 6 illustrates a view similar to Figure 5, but showing the position of the parts during the printing, and registering action of the machine.

Figure 7 illustrates an enlarged fragmental, schematic, sectional view through the meters and multi-ratio driving means therefor.

The novel features of the printing machine illustrated in the drawings, include the provision of independent means for maintaining the selected multi-denomination and multi-ratio means accurately located during the printing action of the machine.

The locating devices are arranged to release the multi-denomination and multi-ratio means while the machine is inactive, in order that these means may be set for a different value.

The particular construction of the printing machine is not of great importance as long as it lends itself to the installation of the above set-forth features.

The printing machine illustrated in the drawings is of known form, and as no claims are directed thereto, it will be briefly described.

Printing machine

The printing machine may include an appropriately formed base casting 10 having a flat bottom portion 11, an integrally cast rear wall 12, and suitable brackets, standards and bearings for operatively supporting the several elements of the machine.

A printer head 13 is suitably mounted upon the forward ends of the spaced swing arms 14 and 15, which arms at their rearward ends, are pivotally mounted upon a cross shaft 16 carried by the base casting rear wall 12.

The under face of the printer head is provided with a printing die 17 having an appropriate type face for the printing of all of a postage stamp, excepting for the denomination thereof. The machine illustrated is adapted to the printing of postage stamps of four different denominations, as, for example, 2, 3, 6, and 10 cents, but may be arranged to print a lesser or greater number of denominations, and denominations printable by the machine may be made to suit

any particular operating condition by providing the machine with appropriate multi-denomination printing and multi-ratio driving means.

The multi-denomination printing means may include providing the printer head with a rotatable member 18, (Figs. 3 and 4), having as illustrated herein, four peripherally spaced denomination printing dies 19.

The four denomination printing dies are as follows: A 2-cent die, 19a; a 3-cent die, 19b; a 6-cent die, 19c; and a 10-cent die, 19d. In Figures 3 and 4, the 2-cent die, 19b, is illustrated in printing register with the printing die 17. A pinion 20 is made fast upon one end of member 18, whereby this member may be rotated to bring any one of the other value printing dies into printing register, by a selector means later to be described.

The machine is provided with a driving mechanism including a drive shaft 21 suitably journaled therein. The rear end of the drive shaft may be extended through the rear wall 12 of the base casting, and provided with one element of an Oldham coupling for making driving connection with any suitable form of driving means, such as, for example, the "Power plant" set forth in the United States Letters Patent No. 1,988,036, issued January 15, 1935, to John Q. Finfrock. The forward end of the drive shaft may be provided with a driving crank 22, which cooperates with an appropriate cam plate 23 carried by the printer head for swinging the printer head into printing relation to a suitable platen 24, which platen is carried by the forward end of the base casting in opposed relation to the printer head.

For each revolution of shaft 21, the printer head will be actuated through one complete printing cycle.

Means are provided for registering the value of each stamp printed, which means may include a subtracting meter 25 and an adding meter 26. These meters are of usual construction, and therefore need not be described in detail. It will be understood that the value of each stamp printed, will be subtracted from the value previously set up in the meter 25, and added to the balance registered in meter 26.

In order to actuate the meters to register therein, a value proportional to the value of each stamp printed, a multi-ratio driving means is provided to form a variable driving connection between the main drive shaft 21 and units wheels of the respective meters. As the multi-ratio driving means is alike for each meter, a brief description for one will suffice for both. The multi-ratio driving means for meter 26 has been chosen for description and includes a main shaft driving gear 27, an idler gear 28, and a spindle gear 29. The spindle gear 29 is fixedly carried upon one end of spindle 30, which spindle may be journaled upon the main meter shaft 31. The spindle is provided with a driving key 32. A ratio sleeve 33 is slidably mounted upon the spindle, and is provided with a key-way cooperating with the driving key 32 whereby the sleeve will be rotated by a rotation of the spindle, but may be freely shifted therealong.

The multi-ratio sleeve may have fastened thereon four ratio gears: 33a, 33b, 33c, and 33d. The ratio gear 33a may be provided with two teeth; gear 33b with three teeth; gear 33c with six teeth; and gear 33d with ten teeth.

The ratio gears above referred to are also provided with a locking surface 34a, 34b, 34c, and 34d. In parallel relation to the meter shaft 31

is a shaft 35, having fastened thereto a ratio pinion 36. Also fastened upon shaft 35 is a units wheel driving pinion 37 maintained in constant driving mesh with the units wheel driven gear 38.

The ratio pinion 36 is provided with a locking disc 39, which cooperates with any one of the following locking surfaces 34a, 34b, 34c, or 34d, which has been moved into register therewith by the selector means to prevent rotation of the ratio pinion until the gear teeth of the selected ratio gear reaches the teeth of the driving pinion during operation of the machine. In this way, the units wheel of the meter will be locked against turning except by the action of the ratio gears and pinion, and also the teeth of the driving pinion will be maintained in position to readily mesh with the teeth of the selected ratio gear when brought into engagement during the operating cycle of the machine.

It will be necessary, of course, to move the correct ratio gear into driving relation with the ratio pinion for the printing of a stamp of selected value, and for this purpose the ratio gears are made to slide longitudinally with relation to the ratio pinion, thereby serially bringing the ratio gears into mesh therewith. It is only necessary, therefore, to provide an operating connection with a hand lever 40 of the selector means.

The means for operatively connecting the selector lever 40 with the ratio sleeve 33, may include providing a reciprocatory shaft 41 slidably mounted in the meter frame in any suitable manner.

A crosshead 42 may be fastened upon the forward end of shaft 41, and may be arranged to engage the annular groove 43 formed in the end of the ratio sleeve to provide a freely rotatable connection with the sleeve, and yet to provide a connection which will cause the ratio sleeve to slide in direct ratio to reciprocatory motion of the shaft.

The shaft 41 may be provided with a depending arcuate finger 44 (Figs. 2, 5 and 6), closely fitting a correspondingly shaped depression 45 formed in the free end of lever arm 46, which lever arm may be fastened upon a transverse shaft 47. The outer end of shaft 41 may be provided with a lever 48 (Figs. 1, 2, 3 and 4), having its free end operatively connected to the selector lever 40 by means of link 49.

The selector lever, through the mechanism just described, may be actuated to slide the ratio sleeve to position any one of its ratio gears in driving relation with the ratio pinion 36.

The selector lever 40 is also connected to the multi-denomination printing means whereby any one of the value printing dies may be brought into printing register. As the multi-denomination and multi-ratio means are both connected to and operated by the selector lever, it is an easy matter to correlate these means so that for each value printing die turned into printing register, the related ratio gear of the multi-ratio means will be positioned in driving relation with the ratio pinion 36, whereby for any denomination selected for printing, a proportional value will be registered in the meters.

The selector lever 40 may be journaled to the machine as by a suitable pivot pin 50, and operatively connected to a selector rack 51 by means of link 52.

The selector rack may be slidably carried by swing arm 53, and provided with rack teeth 54 along its forward under edge, which rack teeth

are at all times maintained in mesh with the teeth of the multi-denomination pinion 20.

Due to the connection between the selector lever and multi-denomination printing means, a movement of lever 40 will cause a proportional turning movement of the multi-denomination printing means whereby any one of the value printing dies 19 may be placed in printing position.

10 A positioning pawl 54 may be pivotally fastened to the machine frame as by means of pivot pin 55, and may be provided at its forward end with a positioning comb 56 having a well-rounded depression 57 for each value of the 15 multi-denomination printing means. The positioning comb is adapted to cooperate with a roller 58 journally mounted upon the side face of the selector lever, and is yieldingly urged into operative relation with the roller by means of spring 20 59, (Fig. 1).

It will be understood that the positioning comb does not lock the selector lever in any one of its printing positions; it merely acts to locate the selector lever at any one of four different 25 positions and to yieldingly maintain the lever at a selected position until forcibly moved therefrom.

When the selector lever is shifted to the first 30 comb notch 57 as illustrated in Figures 1, 3 and 4, the two-cent multi-denomination printing die 19a will be rotated into printing position, and the multi-ratio driving gear 33a, having two teeth, will be shifted into driving relation with the ratio pinion 36. If the machine is now actuated 35 through a printing cycle, a two-cent stamp will be printed and two cents will be added to meter 26 and subtracted from meter 25. If, at the conclusion of the printing cycle the selector lever is shifted to the second comb notch, the three-cent multi-denomination printing die 19b will be turned into printing position, and the 40 multi-ratio driving gear 33b having three teeth, will be shifted into driving ratio whereby during the printing action of the machine a three-cent stamp will be printed, and three cents will be added to meter 26 and subtracted from meter 25.

With the selector lever located in the third comb notch, a six-cent stamp may be printed and registered, and finally when the lever is placed adjacent the fourth notch 57, a ten-cent stamp may be printed and registered.

The machine thus far described is of known form. In the operation of machines of this type, it has been found that in some cases the value 55 printing dies do not correctly register with the stamp printing dies, and as a result thereof, the value is imperfectly printed in the stamp. It is one of the objects of this invention to provide means for correcting this fault, for which 60 purpose I provide a multi-denomination locating means, which will automatically function during the printing action of the machine to locate the selected die in correct printing register, and to so maintain the die until after the completion 65 of the printing operation.

Locating means for the multi-denomination printing die

The locating means for the multi-denomination printing die may include a locating comb 60, (Figs. 1, 3 and 4), which comb may be securely fastened to the base casting in any appropriate manner. The locating comb may be provided with four arcuate upwardly directed guideways 75 having their curvatures concentric with the axis

of cross shaft 16, which shaft pivotally supports the swing arm 15. The four guideways are designated 61a, 61b, 61c and 61d.

In Figure 3 a laterally projecting tooth 62 is shown located directly above the guideway 61a of the locating comb 60, but may be positioned directly above any one of the other guideways by shifting the selector lever to one of its three other positions.

The tooth 62 may be carried by the pivot pin 10 63 which operatively connects link 52 with the selector rack 51.

While the machine is maintained inactive as shown in Figure 3, the tooth will be maintained above and entirely free of the locating comb, thus 15 enabling the selector lever to be freely actuated, but during the printing action of the machine will enter and traverse the selected guideway. The tooth is carried into the selected guideway during the operation of the machine by the selector 20 rack, which is mounted upon the swing arm 15.

The entrance end of each of the guideways is suitably expanded, whereby should the selector lever for any reason fail to accurately align the tooth with its selected guideway, the tooth 25 will be nicely guided therein. As tooth 62 is carried by the selector rack, and as this rack in turn directly meshes with pinion 20 which is fastened to the multi-denomination printing means, it follows that the engagement of tooth 30 62 with its selected guideway will maintain the selected denomination printing die in correct printing register during the printing action of the machine.

Should the selector lever for any reason fail 35 to correctly align tooth 62 with the selected guideway, the tooth will be guided therein due to the well-rounded engaging edge of the tooth and to the expanded entrance end of the guideway, and will thereby act to move the selector 40 rack 51 sufficiently to correctly locate the selected printing die.

From the above description it will be appreciated that I have provided means which will function to not only correctly locate the selected printing die in printing register, but will also function to maintain the die located in printing register during the printing action of the machine. 45

It should also be appreciated that by this tooth and comb locating means, that the multi-denomination printing means will be securely locked in 50 its adjusted position during the operating cycle of the machine, and will thus be securely guarded against misuse.

It is likewise important to provide means for 55 maintaining the selected ratio gear in correct driving relation to the ratio pinion 36, whereby a correct value will be entered into the respective meters for each operation of the machine.

Locating means for the multi-ratio driving means 60

The locating means for the multi-ratio driving means may include (Figs. 1, 2, 5 and 6), a locating comb 70 fastened to the inner face of the swing arm 14, (Fig. 2), as by means of a 65 channel-shaped spacer 71 and rivets 72. The locating comb 70 may be provided with four downwardly directed open-ended guideways 73a, 73b, 73c and 73d. The lever arm 46 of the multi-ratio shifting means may be provided with a 70 downwardly extending arm 74, having a laterally projecting roller pin 75 suitably fastened to its free end. A roller 76 may be journaled upon pin 75, and may cooperate with the locating comb guideways in a manner to be described. 75

The ends 77 and 78 of the locating comb may be made of sufficient length to engage the roller 76 at each end of its normal travel to prevent over-travel of arm 74, and thereby acting to prevent over-travel of the ratio sleeve 33.

The guideways 73a, 73b, 73c and 73d are formed in the locating comb between the ends 77 and 78.

Figure 5 illustrates the machine at rest and in this figure it may be noted that the roller 76 is in alignment with, but clear of the two-cent guideway 73a. By means of the selector lever, the roller may be shifted into alignment with any one of the other three guideways.

If it is desired to print a two-cent stamp, the selector lever will be left in its two-cent printing position as illustrated in Figures 1 and 3, which will place roller 76 in alignment with the two-cent guideway 73a. During the operation of the machine the comb 70 will be swung downwardly, due to its connection with swing arm 14, to a position as shown in Figure 6, wherein the guideway 73a has moved down over roller 76.

As roller 76 is carried by arm 74 of the lever 46, which lever controls the movement of the ratio sleeve 33 through the mechanism previously described, it follows that the movement of the selected guideway, in this case the two-cent guideway 73a, down over the roller, will accurately locate the two-cent ratio gear 33a in correct driving relation with the ratio pinion 36. The roller and guideway also form a locking means for locking the selected ratio gear in its correct driving relation during the operation of the machine.

In case the selector lever does not accurately align roller 76 with a selected guideway, the roller will enter the guideway due to its cylindrical form and the well-rounded entrance to guideway, and in doing so, will shift the ratio sleeve to correctly align the selected ratio gear with the ratio pinion, thereby insuring a proper functioning of the machine.

When the selector lever is positioned in the next or three-cent notch 57 of the selector positioning comb, the roller 76 will be moved into substantial alignment with the three-cent guideway 73b. This same movement of the selector lever will act to shift the multi-denomination locating tooth 62 into substantial alignment with the three-cent guideway 61b of comb 60.

If the machine is now operated, the multi-denomination locating tooth 62 will enter guideway 61b while the multi-ratio guideway 73b will move to engage roller 76, whereby the three-cent printing die 19b will be accurately located in printing register, and the three-cent multi-ratio gear 33b will be correctly located in driving relation with the ratio pinion 36, and as a result thereof the value of three cents will be clearly printed with the printing of the stamp, and this same value will be added in meter 26 and subtracted from the balance remaining in meter 25.

By shifting the selector lever to the next or six-cent notch of the selector locating comb 55, the multi-denomination location tooth 62 will be moved into substantial alignment with the six-cent guideway 61c, while the multi-ratio roller will be swung into substantial alignment with the

six-cent guideway 73c. If the machine is placed in operation, the locating means will function as previously described, to insure a clear and distinct printing of a six-cent value in the stamp and the registration of this figure in the respective meters.

When the selector lever is moved to the last or ten-cent notch, tooth 62 will move into substantial alignment with the ten-cent guideway 61d, while roller 76 will be swung into substantial alignment with the ten-cent guideway 73d, and during the operation of the machine these devices will act to maintain the ten-cent printing die 19d located in correct printing register, and the ten-cent ratio gear 33d in correct driving relation with the ratio pinion 36, whereby the value of ten cents will be clearly printed, and this same amount will be added and subtracted from the respective meters.

Should the selector means fail, for any reason, to place the selected printing die in correct printing register, the multi-denomination locating means will function during the initial portion of the operating cycle of the machine to positively actuate the selected printing die into correct printing register, and will act to maintain the die so registered until after the printing operation. Likewise, should the selector means fail, for any reason, to place the selected ratio gear in correct driving position, the multi-ratio locating means will function during the initial position of the operating cycle of the machine, to positively shift the selected ratio gear into correct driving ratio, and will maintain the ratio gear so positioned until after the completion of the registering operation.

A further advantage derived from the use of these features, is the positive locking of the multi-denomination printing and multi-ratio driving means in their selected positions during the operating cycle of the machine, whereby even by means of the selector, they cannot be changed after the machine has started upon its operating cycle.

Having fully described a preferred form of the invention, it is to be understood that the foregoing description is for illustrative purposes only, and I do not desire to be limited by any of the details shown or described, except as defined in the appended claim.

I claim:

In a multi-denomination printing machine, an oscillatory frame, a printer head carried thereby, multi-denomination printing means operatively mounted in said head and having a plurality of value printing dies, selector means operable for actuating the multi-denomination printing means to present any one of the value printing dies to printing register, a member of said selector means being operatively carried by said frame, comb means fixedly mounted in the machine and having an appropriate guideway for each selective denomination, and a locking tooth carried by said member arranged to engage the related comb guideway for the selected denomination during a predetermined portion of the oscillatory motion of said frame for maintaining the multi-denomination printing means in correct printing register with the printer head.

FRANK P. SAGER.
